ELECTRIC SWITCH

Everett C. Brown, Louisville, Ky., assignor to
 Cheatham Electric Switching Device Co., Incorporated, Louisville, Ky., a corporation of Kentucky

Application August 12, 1940, Serial No. 352,189

4 Claims. (Cl. 200—151)

My invention relates to manually operating electric switches.

An object of my invention is to provide a switch capable of completing and interrupting a circuit carrying high amperage, high voltage direct current.

Another object of my invention is to provide a combination of mechanical elements, organized for providing an electric switch equipped with means for minimizing electrical erosion of the contact points by "splitting" the electric arc incident to the interruption of currents of the above designated class flowing through said points and thereby provide an electric switch that will be dependable over a long period of service and one that can be readily serviced in the event either mechanical failure or electrical erosion develops.

Another object is to mount an arc splitting shield directly on the main operating lever and dispose it for travel between the contact points of the switch, instantly upon the separation thereof.

A further object is to provide a switch having a main arm that can be manually operated from a rest position for effecting engagement of electrical contacts and then released from substantially any operated position for an automatic return to the normal rest position and consume a substantially uniform period of time independently of the speed with which the actuating lever is manually operated before release.

My invention resides in the new and novel construction, combination and arrangement of the various parts hereinafter fully described and disclosed in the drawing.

In the drawing accompanying the specification:

Figure 1 is a plan view of my electric switch, complete, except the end of the hand grip is not shown;

Figure 2 is a side elevation of Figure 1;

Figure 3 is a section of Figure 2 along lines 3—3;

Figure 4 is a section of Figure 2 along lines 4—4;

Figure 5 is a section of Figure 2 along lines 5—5.

In the preferred construction embodying my invention, I employ a base member composed of an insulating material designated by numeral 10. Secured to the base in vertical arrangement thereto is stationary contact post 11 on the top of which is permanently fixed contact 12 of arc

resisting material; also attached in vertical relation to the base by nut 13 is stud 14, which stud provides a bearing for the main operating lever 15 of insulating material, such as hardwood.

5 A cross shaft 21 extends through a hole in stud 14 adjacent the upper end thereof and secured therein by screw 22, the latter also secures cross bar 23 and terminal 24. Pivoted on shaft 21 are the hubs 25A, 25B of arm 25, on this arm is mounted contact 26 so as to register with contact 12. Arm 25 can be oscillated from the normally open position, shown by the full lines, to the closed position as shown by the broken lines. Springs 25C—25D surround hubs 25A, 25B respectively, and serve to bias arm 25 to the closed position, also to retain roller 25E against cam track 29 except when contact 26 is engaged with contact 12 for short periods of time when lever 15 is moved from the normal position to the operated or broken line position. The roller is mounted on shaft 27, which shaft in turn extends through arm 25 as shown in Figs. 2 and 5, and is located for engagement with and operated by cam track 29, which track is an integral part of cam plate 28, the latter is attached to lever 15. It can be noted from Figures 1, 3 and 5, that cam plate 28 is carried by lever 15, and is mounted on the "arc splitter" 30 and that both of these members are secured to the lever by screws 31 and nuts 32.

The stud has an enlarged section 14A around which is lodged a conventional double acting centering spring 16 having ends 17, 18 disposed in substantially the same plane for engagement with lug 19 carried on the bottom face of the lever, also for engagement with lug 20 attached to the base. This spring is manipulated by and functions to retain lever 15 in the normal position 40 shown by the full lines in Figures 1 and 2, also to return said lever to this position after it has been manually operated to the position indicated by dotted lines and released as shown in Figure 1. It should be noted that as lever 15 is manually moved from the full line position to the dotted line position lug 19 carries spring end 17 with it and places spring 16 under tension and that, upon release of arm 15 by the operator, the force stored in the spring will produce an overthrow of the arm in the opposite direction, and that as the arm reaches the central or vertical position, lug 19 engages spring end 18 and leaves end 17 engaged with lug 20, thus absorbing the 50 force of the arm. Spring 16 finally brings arm 55

15 to the rest position as shown by the full lines of Figures 1 and 2.

Although the foregoing description and drawing disclose a preferred embodiment of my invention, modifications can be made without departing from the spirit of this invention, therefore I wish to be limited only by the claims presented herewith.

I claim:

1. A manually operated switch, comprising in combination, a base; a pair of posts mounted on said base in vertical relation thereto; a stationary contact mounted on one of said posts; a contact arm having a contact mounted thereon for engagement with and normally out of engagement with the stationary contact and pivotally mounted on a shaft traversely attached adjacent the top of the other post; a spring operably associated with said other post and said arm for biasing the latter for effecting engagement of the contacts; an operating lever pivotally mounted on the said other post; means mounted on said lever for raising said arm against said spring for effecting separation of said contacts and an arc splitting shield mounted on said lever and disposed for movement between said contacts only when said contacts are separated.

2. A manually operated switch, comprising in combination, a base; a pair of posts mounted on said base in vertical relation thereto; a stationary contact mounted on one of said posts; a contact arm having a contact mounted thereon for engagement with and normally out of engagement with the stationary contact and pivotally mounted on a shaft traversely attached adjacent the top of the other post; a spring for biasing said arm the latter for effecting engagement of the contacts; an operating lever pivotally mounted on the said other post; means mounted on said lever for raising said arm against said spring for effecting separation of said contacts

and an arc splitting shield mounted on said lever and disposed for movement between said contacts only when said contacts are separated.

3. A manually operated switch, comprising in combination, a frame; a contact post and a pivot post on said frame; a stationary contact mounted on one of said posts; a contact arm having a contact in register with and normally out of engagement with the stationary contact and pivotally mounted on the other of said posts; a spring operably associated with said arm for biasing the contact thereof for engagement with the stationary contact; an operating lever pivotally mounted on the pivot post; means mounted on said lever for raising said arm against said spring for effecting separation of said contacts; an arc splitting shield mounted on said lever and disposed for movement between said contacts, and a spring surrounding the stationary post, said spring having arms engaging stops, one of the latter mounted on the operating lever and the other stop attached to the frame.

4. A manually operated switch, comprising in combination; a base; a stationary contact mounted thereon; a shaft mounted on said base in vertical relation thereto; a contact arm pivotally mounted on said shaft and equipped with a contact for engagement with the stationary contact; a spring operably associated with and biasing said arm for engagement of the contact thereon with the other contact; an operating lever pivotally mounted on said shaft for operating said arm; means operatively associated with said lever for raising said arm against the force of said spring for effecting and retaining separation of said contacts when said lever is at rest and for releasing said arm for closing said contacts in response to the force of said spring, upon operation of said lever from said rest position.

EVERETT C. BROWN.
